UNITED STATES PATENT OFFICE.

ADDISON N. CALKINS, OF QUINCY, ILLINOIS.

METALLIC WAGON RUNNING-GEAR.

No. 836,240.

Specification of Letters Patent.

Patented Nov. 20, 1906.

Application filed February 27, 1906. Serial No. 303,267.

To all whom it may concern:

Be it known that I, ADDISON N. CALKINS, a citizen of the United States, residing at Quincy, in the county of Adams and State of Illinois, have invented certain new and useful Improvements in Metallic Wagon Running-Gear; and I do hereby declare the following to be a full, clear, and exact description of the same, reference being had to the accompanying drawings, forming a part of this specification, and to the letters of reference marked thereon.

This invention relates to improvements in the running-gear of wagons, and particularly running-gear made solely or chiefly of metal, the objects of the invention being to provide a gear of strong but simple construction and adapted to withstand hard wear and rough usage.

Further objects of the invention are to provide a structure the parts of which may be manufactured economically and assembled with the greatest facility.

The invention consists in certain novel details of construction and combinations and arrangements of parts, all as will be now described, and pointed out particularly in the appended claims.

Referring to the accompanying drawings, Figure 1 is a perspective view of a wagon running-gear embodying the present improvements. Fig. 2 is a front elevation of the front axle and bolster. Fig. 3 is a similar view of the rear axle and bolster, one end being shown partly in section. Figs. 4 and 5 are vertical sections on the lines 4 4 and 5 5, respectively, Fig. 2. Fig. 6 is a horizontal section on the line 6 6, Fig. 2. Fig. 7 is a vertical section on the line 7 7, Fig. 3.

Similar letters of reference indicate like parts in the several figures.

The bodies of the axles are a composite structure, each embodying two pressed-steel plates united by rivets, the upper edges of the plates being oppositely flanged and the flanges seated within and united to an inverted channel-iron, the flat face of which thus constitutes the top of the structure.

The two pressed-steel axle-plates referred to are indicated in the drawings by the letters A A', each having its upper edge flanged outwardly at B B' and each having a substantially horizontal semicylindrical recess therein at C C'. When brought together and united by rivets, the recesses C C' inclose the

axle lettered D, and it will be understood that this axle D may be tubular, as shown, or solid or may consist of short sections or stubs D', as shown in Fig. 3.

The flanges B B' of the plates are sur- 60 mounted by an inverted channel-iron E, secured to the flanges by riveting, and the flanges l of the channel-iron preferably extend some distance below the edges of the flanges B B', so as to effectually brace and 65 unite the structure into a homogeneous whole and the upper flat face of which forms a wide bearing-surface for supporting whatever may be placed upon it.

Where the stakes are rigid with the axle, 70 as shown in Fig. 3, the ends of the channel-iron are turned up, as at E', and they are supported in this position and the whole structure made solid by vertically-extending brace-plates G G', Fig. 6, flanged at their inner edges at g g' and united to the plates A A' at their lower ends by rivets. These plates G G' constitute stake-braces, and besides being riveted together and to the channel-iron they carry the stake-rings H, which 75 may be held by pivots passing through the plates, so as to form a permanent but loose attachment.

The front axle carries at the center a bolster-plate I, secured in place on top of the 85 channel-iron, and resting on this bolster-plate is a second bolster-plate I', secured to the bottom of the bolster. The bolster itself is formed of pressed-steel plate K K', flanged at k along the upper edges to receive a chan- 90 nel-iron L and at k' to rest on the bolster-plate I'. The bolster-stakes are formed by bending the ends of the channel-iron up and reinforcing them by pressed-steel plate over- 95 lapping and secured to the ends of the bolster, as before described in connection with the rear axle.

The plates K K', forming the bolster, and the front axle-plates A A' are both formed with vertical recesses, preferably by being 100 pressed out centrally, for the reception of the king-bolt M, which latter passes vertically between the plates K K', through the channel-iron on the axle and between the axle-plates A A', and through the axle itself, 105 where the latter extends from side to side of the wagon.

To prevent wear on the plates, the socket for the king-bolt is preferably reinforced by an additional thickness of metal, as at N, Fig. 5, 110

and the king-bolt is held in place by a cross-rivet *m* in the bolster, but does not project through the top of the bolster.

The reach *O* passes through openings in 5 the plate of the front and rear axles, and the plates at the edges of the openings are preferably flanged, as at *o*, Fig. 5, to afford additional bearing-surface, as will be readily understood.

10 Rear hounds formed of channel-iron *P* are riveted at their rear ends to the plates of the rear axle above the axle itself, and braces *P'* extend from the plates below the axle to the channel-irons a short distance in rear of their union. Thus the parts are held rigidly and braced against a possibility of being twisted out of shape.

To relieve strain on the king-bolt, the front axle is provided with a rearwardly-extending circle *Q*, formed of angle-iron, riveted to 20 the axle-plates and working through a guide *Q'* on the reach.

Where a tubular axle is employed, its ends are tapered, as shown in Fig. 3, and the skein 25 *R* is held in place thereon by a nut *r* on a central bolt *r'*, anchored in an internal tapered plug *r''*, and the nut *S* for retaining the wheel is formed with an opening of sufficient size to pass over the nut *r*.

30 The construction of the gear, it will be seen, is exceedingly simple and the parts serve to mutually reinforce each other, this being especially apparent in the overlapping of the stake-braces, plates, and axle-plates, 35 and in the united channel-irons and flanges of the plates. All of the transverse supports between the wheels—*i. e.*, the axles and bolster—are of the double pressed-steel and channel-iron construction, thus permitting of 40 the use of practically uniform stock throughout.

Having thus described my invention, what I claim as new, and desire to secure by Letters Patent, is—

45 1. In a running-gear for wagons the combination of pressed-steel plates flanged outwardly at their upper edges and connected rigidly together face to face and an inverted channel-iron within which said flanges are 50 seated and to which they are rigidly secured to form a transverse support between the wheels; substantially as described.

2. In a running-gear for wagons, a transverse support embodying pressed-steel plates 55 riveted together and having their upper edges flanged outwardly in opposite directions and a channel-iron secured to said flanges and with its own flanges embracing the flanges of the plates; substantially as described.

60 3. In a running-gear for wagons, a transverse support embodying pressed-steel plates secured rigidly together face to face and formed with opposite recesses constituting 65 iron holding-chambers in the structure and

oppositely-flanged upper edges and a channel-iron secured to said flanges and with its own flanges embracing the flanges of the plates; substantially as described.

4. In a running-gear for wagons, a transverse support embodying pressed-steel plates secured rigidly together and having opposite longitudinal recesses and oppositely-flanged upper edges, an axle mounted in the chamber formed by the opposite recesses and an inverted channel-iron seated over and secured rigidly to the flanges of the plates; substantially as described.

5. In a running-gear for wagons a transverse support embodying pressed-steel axle-plates secured rigidly together and having opposite recesses and oppositely-flanged upper edges, an axle mounted in the chamber formed by the recesses, upwardly-extending brace-plates overlapping and secured rigidly 85 to the ends of the axle-plates and having their inner edges flanged in opposite directions, and an inverted channel-iron bent to embrace the flanges of the axle-plates and flanges of the brace-plates and forming with 90 the brace-plates stakes at the ends of the axle; substantially as described.

6. In a running-gear for wagons, a transverse support embodying metal plates secured rigidly together face to face and flanges 95 in opposite directions at the upper edges, an inverted channel-iron secured to and embracing said flanges and having its ends bent upwardly to form stakes and brace-plates for said stakes; substantially as described.

7. In a running-gear for wagons, a transverse support embodying metal plates secured rigidly together face to face with their upper edges flanged in opposite directions, an inverted channel-iron secured to and embracing said flanges and having its ends bent upwardly to form stakes and brace-plates for said stakes having their inner edges flanged in opposite directions and their lower ends overlapping and secured rigidly to the ends 100 of the plates forming the transverse support; substantially as described.

8. In a running-gear for wagons the combination with the rear axle, axle-plates embracing the axle and secured together face to face, an inverted channel-iron secured on the upper edge of the plates, and a reach, of a front axle, axle-plates embracing the front axle and secured together face to face and having their upper edges flanged in opposite 105 directions, an inverted channel-iron secured to and embracing said flanges and a king-bolt passing vertically through the channel-iron and between the axle-plates below the channel-iron; substantially as described.
